CYLINDER LOCK

Herbert W. Brooks, West Haven, Conn., assignor
to Sargent & Company, New Haven, Conn., a
corporation of Connecticut

Application December 9, 1943, Serial No. 513,545

5 Claims. (Cl. 70—363)

This invention relates to locks, and more particularly to a lock of cylindrical form which may be employed in any relation in which a key-operated lock is desired.

Locks of this type very often employ so-called pin tumblers in that they are provided with sectional pins extending transversely of a slotted key barrel, so that when the key is inserted in the slot in the key board the breaks in the pins will be aligned to permit rotation of the barrel. Other cylinder locks are provided with a plurality of disks or plates slotted to receive a key, the bit of which aligns these plates with the key barrel so that the latter may be turned.

The present lock, however, distinguishes from both forms of locks described above in that there are provided within the lock case a plurality of disks or plates superposed one upon the other. One of these disks is fixed with respect to the lock case, while the others are rotatable with respect to the case. The rotatable disks are locked to the fixed disk by means of sectional pins similar in some respects to the pin tumblers described above, in that, while they normally prevent rotation of the rotatable disks with respect to the fixed disk, the breaks in these sectional pins can be aligned so as to permit such rotation. In the present instance the pins extend longitudinally of the key instead of transversely thereof, so that they extend transversely of the disks or plates and are pushed inwardly by the key to be properly aligned.

One object of the present invention is to provide a cylinder lock of novel construction.

A further object of the invention is to provide a novel form of cylinder lock comprising a plurality of superposed disks and pins extending longitudinally of the axis of the lock to normally lock the disks together.

A still further object of the invention is to provide a cylinder lock of novel construction having a plurality of superposed disks mounted within a lock case, at least one of which disks is held against rotation and others of the disks locked to the secured disk by sectional pins designed to be aligned by a key such that rotation of the movable disks may be effected relatively to the fixed disk and thus serve to operate a rollback or other locking member.

To these and other ends the invention consists in the novel features and combinations of parts to be hereinafter described and claimed.

In the accompanying drawing:

Fig. 1 is a sectional view of a lock embodying my invention;

Fig. 2 is also a sectional view on line 2—2 of Fig. 1;

Fig. 3 is a sectional view on line 3—3 of Fig. 1;

Fig. 4 is a sectional view on line 4—4 of Fig. 1; and

Fig. 5 is a sectional view similar to Fig. 1, but showing the pin tumblers aligned by the key to permit operation of the lock.

I have shown in Fig. 1 of the drawing a lock comprising a casing formed of a cup-shaped body portion 10 and a cap or face member 11, the latter overlapping the body of the casing, as shown at 12. Within the casing thus formed are inner and outer shells 13 and 14, these shells being generally of cup-shaped form, the outer one of which is provided with a key slot 15 which registers with the key opening 16 in the cap 11 of the casing. The inner shell 13 is also provided with an opening 17 which registers with an opening 18 in the body 10 of the casing.

The two shells 13 and 14 are spaced apart by a disk 19 which fits fairly snugly within the body portion 10 of the casing, but is provided with diametrically opposite recesses 20 designed to receive the transversely turned ends 21 of lugs extending upwardly from the cap 11 so that the disk 19 is secured against movement relatively to the casing. This disk, as will be explained hereinafter, serves as the locking disk to secure the parts against rotation. It will be apparent from Fig. 4, for example, that the disk 19 is substantially of the same diameter as the inner diameter of the casing portion 10, so that it will lie between the ends of the inner and outer shells 13 and 14 and space these shells apart.

Within the shells 13 and 14 and on each side of the disk 19 are provided a plurality of rotating disks 22 all of similar form and shape. Any desired number of these disks may be provided as 40 desired. As shown, three are provided on each side of the disk 19, or six of the disks 22 in all.

These disks, as shown in Fig. 3, are of generally circular form and lie within the surrounding shells. They are, however, provided at diametrically opposite points with lugs 23 which fit within slots 24 in the shells so as to lock these disks to the shells. As will also be apparent from Fig. 3 and Fig. 4, the disk 19 is provided with openings 25 and the disks 22 with openings 26 which register with the openings 25 and with each other when the lugs 23 of the disks are aligned, so that the openings 25 and 26 form a continuous opening or recess longitudinally of the lock casing or parallel to its axis.

Within these recesses are mounted sectional

pins 27 urged forwardly or toward the front face of the lock by springs 28. As many of the openings 25 and 26 may be provided as desired, but as shown two are provided in each of the plates 19 and 22 so that the lock will accommodate two of the sectional pins 27. It will be seen from Fig. 1 of the drawing that when the pins 27 are in their forward positions, in which they are maintained by the springs 28, the breaks between the sections of the pins do not register with the inner and outer surfaces of the disk 19, so that these pins lock the adjoining disks to the disk 19. As the latter is held against rotation relatively to the casing, and as the forward and rear disks 22 are secured together by reason of the fact that they are secured to the shells 13 and 14 by the lugs 23, the rotation of the disks 22 and shells 13 and 14 will be prevented.

When it is desired to operate the lock a proper key 29 is inserted through the key slots 15 and 16, the key being provided with a central bit portion 30 which is received in slots 31 in the plates 22 and a circular opening 33 in the plate 19. The key 29 is also provided with pin-actuating members or arms 34 and 35, which engage below the sectional pins 27 and raise these pins until the breaks therein register with the inner and outer surfaces of the disk 19, as shown in Fig. 5. At this time if the key is turned the inner and outer disks 22 will be rotated together with the shells 13 and 14, as the key fits snugly in the slots 31. The disk 19 will remain stationary, however, due to its connection with the casing, and the key is permitted to rotate therein due to the fact that this disk is provided with a circular opening 33 of a diameter equal to or slightly larger than the width of the key bit. It will be understood that the key slot 16 in the outer casing is of such a shape as to permit insertion and withdrawal of the key only in one position, and therefore the parts must be turned back to their original position before the key is withdrawn. When the key is withdrawn, however, the sectional tumblers 27 will be forced outwardly by their springs 28 and the parts will again be in locked position.

An actuating member or post 36 is rotatably mounted at the inner end of the casing and secured to the inner shell 13, which operating member may actuate a locking device of any desired form. This member is provided with a reduced inner end 37 which passes through the openings 17 and 18, and a lug or key 38 on the part 37 serves to secure it non-rotatably to the shell. Also the enlarged portion of the member 36 may be slightly longer at one point to provide the shoulder 39, which is adapted to engage a shoulder or lug 40 extending inwardly from the edge of the opening 18 to limit the rotation of the post. It will be apparent, therefore, that when the disks 22 are rotated and the shell 13 rotated by reason of the connection of these disks with the shell, the post 36 will also be rotated, as permitted by the shoulder or shoulders 39, which will serve to actuate any locking device connected to the rotating post.

While I have shown and described a preferred embodiment of my invention, it will be understood that it is not to be limited to all of the details shown, but is capable of modification and variation within the spirit of the invention and within the scope of the claims.

What I claim is:

1. A lock structure comprising a generally cylindrical casing, a pair of cup-shaped members rotatably mounted therein with their open ends 5 facing each other, a plurality of disks non-rotatably mounted in each of said members, an additional disk mounted between said members and secured against rotation in the casing, all of said disks having registering openings therein 10 and sectional pins slidably mounted in said openings.

2. A lock structure comprising a generally cylindrical casing, a pair of cup-shaped members rotatably mounted therein with their open ends 15 facing each other, a plurality of disks in each of said members, the latter having slots formed in the walls thereof and the disks having projecting lugs disposed in said slots to secure the disks non-rotatably to the member, an additional disk mounted between said members and secured against rotation in the casing, all of said disks having registering openings therein and sectional pins 20 slidably mounted in said openings.

3. A lock structure comprising a generally cylindrical casing, a pair of cup-shaped members rotatably mounted therein with their open ends 25 facing each other, a plurality of disks non-rotatably mounted in each of said members, an additional disk mounted between said members and secured against rotation in the casing, said disk having a notch formed in the edge thereof, said casing consisting of a body portion and a cap portion, said cap portion having lugs disposed in said notches to secure the disk non-rotatably to the casing, all of said disks having 30 registering openings therein and sectional pins slidably mounted in said openings.

4. A lock structure comprising a generally cylindrical casing consisting of a body portion and 40 a cap portion, the latter having lugs turned inwardly and projecting through openings in the body portion, a disk mounted in said casing and being engaged with the inturned ends of said lugs to prevent rotation thereof relatively to the casing, a plurality of additional disks on each side 45 of said first-named disk, said additional disks being rotatably mounted in the casing, all of said disks having registering openings therein and sectional pins 50 mounted in said opening, and a post projecting from the body portion of the casing, and means connecting said post to said additional disks to be rotatable therewith relatively to the casing.

5. A lock structure comprising a generally cylindrical casing consisting of a body portion and a cap portion, the latter having lugs turned inwardly and projecting through openings in the body portion, a disk mounted in said casing and being engaged with the inturned ends of said lugs to prevent rotation thereof relatively to the casing, a plurality of additional disks on each side 55 of said first-named disk, said additional disks being rotatably mounted in the casing, all of said disks having registering openings therein and sectional pins 60 mounted in said opening, a post projecting from the body portion of the casing, means connecting said post to said additional disks to be rotatable therewith relatively to the casing, and cooperating means on said casing and post to limit rotation of the latter.

HERBERT W. BROOKS.
